[57] CLAIM

The ornamental design for a combined resectoscope handle and latch, as shown and described.

DESCRIPTION

FIG. 1 is a perspective view of a combined resectoscope handle and latch, showing our new design;

FIG. 2 is a side elevational view, the opposite side being a mirror image thereof;

FIG. 3 is a front elevational view thereof;

FIG. 4 is a rear elevational view thereof;

FIG. 5 is a top plan view thereof; and

FIG. 6 is a bottom plan view thereof.

The broken lines showing of the resectoscope is for illustrative purposes only and forms no part of the claimed design.

FIG. 1.FIG. 2.FIG. 3.FIG. 4.FIG. 5.FIG. 6.
